UNITED STATES PATENT OFFICE.

EDWIN D. McCACKEN, OF NEW YORK, N. Y., ASSIGNOR TO LUCIUS A. BIGELOW, TRUSTEE, OF BOSTON, MASSACHUSETTS.

IMPROVEMENT IN GAS-LIGHTERS.

Specification forming part of Letters Patent No. 136,084, dated February 18, 1873.

To all whom it may concern:

Be it known that I, EDWIN D. McCACKEN, of the city, county, and State of New York, have invented an Improvement in Apparatus for Lighting Illuminating Gas, of which the following is a specification:

The object of this invention is to provide for the letting on and shutting off the gas to and from all or any number of the street or other lamps or gas-burners in a city, town, or district, or all or any number of the burners in any building, hall, or apartment, by means of a single main cock or valve located in a central or other convenient place, without interfering with any lamps or burners to and from which it may be desired to let on or shut off the gas independently.

In carrying out my invention I use a reservoir of air or gas, preferably air, at a pressure higher than that of the illuminating gas, in connection with a system of main and service pipes corresponding with the ordinary system of main and service pipes which supply the illuminating gas; and I employ in connection with each burner or group of burners to and from which the gas is to be let on and shut off, as above mentioned, a valve-box connected with the service-pipe which supplies the illuminating gas and also with the compressed-air or gas pipe, such valve-box containing a valve which lets on and shuts off the gas from the burner or group of burners, and a diaphragm with which the said valve is connected, and which is so operated by the turning on of the main valve in the compressed-air or gas main as to produce the opening or closing of the said connected valve. I further employ, in proper relation with each illuminating-gas-burner, a smaller pipe and burner, which are also in connection with the valve-box aforesaid, or with the service-pipe which supplies the said box, such smaller pipe not having the gas shut off from it by the diaphragm and connected valve aforesaid, but always supplying gas to its own burner in a small jet, which is always kept lighted, and by which the gas, when let on to the illuminating-burner is ignited.

My invention consists mainly in the novel construction of the valve-box and novel arrangement of its valve and diaphragm, and of the pipes in connection with it, whereby the

operation of letting on, lighting, and shutting off the gas is effected.

The drawing illustrates, in vertical section, the application of the invention in connection with a single burner.

A is the valve-box, of suitable form and size, divided by fixed partitions R and a and a flexible diaphragm, D, into four compartments or chambers, B¹, B², B³, and B⁴, with the first or lowest one, B¹, of which the ordinary service or supply pipe E from the illuminating-gas main is connected, and with the third one, B³, of which, next above the flexible diaphragm D, the small service or supply pipe G from the high-pressure air or gas main is connected. The uppermost compartment B⁴ has connected with it the pipe M, to which the illuminating-burner L is attached, and the lowest one, B¹, has connected with it the small pipe H, to which the igniting-burner J is attached. The two compartments B² and B⁴ are connected by a short pipe, e, which passes outside of the compartment B³, and these two constitute, virtually, a single chamber. In the center of the partition a there is an air-opening, in which is the seat for the valve S, which opens with a downward movement, and which has applied to its stem d a spiral spring, K, which exerts an upward pressure upon it, and a consequent tendency to close it. The upper part of the said stem is connected with the flexible diaphragm D. Guides b and c are attached to the partition a to keep the valve-stem upright. The pipe H is fitted with a valve or cock, I, of any kind which is capable of a very fine adjustment to regulate the supply of gas to the igniting-burner to produce a very small jet. The illuminating-burner L has provided in one side, and extending upward to its tip, a small groove, x, into which the tip of the igniting-burner J enters, and in which the jet of flame from the latter burner is concealed during the day-time and protected from being blown out, and by which the said jet is directed to the tip of the illuminating-burner L.

The operation is as follows: The lower compartment B¹ of the valve-box is always kept filled with gas, and furnishes, through the pipe H, a supply to the igniting-burner, which is intended to be always kept lighted. The spring K keeps the valve S closed, and so prevents any gas from being supplied to the burner L.

until the compressed air or high-pressure gas is turned on by the cock or valve at the central or other station, when such air or gas, entering by the pipe G into the chamber B³, presses down the diaphragm D and opens the valve S, allowing the illuminating-gas from the pipe E and chamber B² to enter the chamber B⁴, whence it passes freely to the chamber B⁴, and thence, by the pipe M, to the burner L. On issuing from the burner the gas is ignited by the jet from the igniting-burner J. When the gas at this illuminating-burner is to be put out the cock or valve in the compressed-air or high-pressure main is closed, and the spring K closes the valve S, shutting off the gas, except from the igniting-burner J, where sufficient flame is left for lighting up again.

It will be understood that any number of burners or sets or groups of burners connected in a similar manner with the gas and compressed-air pipes, and furnished each with a similar valve-box and valve, may simultaneously be operated upon in a similar manner by the opening and closing of a single valve or cock suitably placed in the compressed-air main.

When one valve and diaphragm are to be used for a set or group of burners the valve-box may have attached to it either a number of pipes, H, corresponding with the number of

burners or a single pipe, H, with a number of branches corresponding with the number of burners.

In the application of the invention to street-lamps it is desirable, in order to prevent the blowing out of the very small flame which is left at the burners J when illumination is not required, that the bottom of the lamp should be made of finely-perforated metal or wire gauze which will admit air enough for combustion at all times, but prevent gusts or strong drafts of wind from entering the lamp.

What I claim as my invention, and desire to secure by Letters Patent, is—

1. The arrangement within and in connection with the valve-box A of the fixed partitions R a, diaphragm D, valve S, spring K, and pipes E, G, M, H, and e, substantially as herein described, whereby the entire operation of letting on, lighting, and shutting off the gas is effected by the action of a single valve within the box.

2. The groove x in the illuminating-burner, in combination with the igniting-burner, substantially as and for the purpose herein set forth.

E. D. McCACKEN.
